UNITED STATES PATENT OFFICE.

BERNARDUS PETRUS MOORS, OF HAGUE, HOLLAND.

GAS-METER.

SPECIFICATION forming part of Letters Patent No. 429,313, dated June 3, 1890.

Application filed September 20, 1889. Serial No. 324,585. (No model.)

To all whom it may concern:

Be it known that I, BERNARDUS PETRUS MOORS, a subject of the King of Holland, residing at Hague, in the Kingdom of Holland, 5 have invented new and useful Improvements in Wet Gas-Meters, of which the following is a specification.

My invention relates to improvements in wet gas-meters of the ordinary well-known 10 kind, whereby all the defects adhering to these apparatus are obviated—such as the possibility of taking unmeasured quantities of gas from the meter, the inconstant water-level in the meter, by which it is impossible to measure in an exact manner, and the lamps are caused to flicker when the siphon becomes 15 filled. The repeated filling of the gas-meter and the uncertainty about the water-level in the gas-meter are remedied by the improved 20 construction of the gas-meter.

By applying the hereinafter-described improvements the water-level of the gas-meter is rendered constant and the measuring operation may be effectuated with a nearly 25 mathematical exactness; the descending of the water-level, caused by the evaporation of the water in the gas-meter, is continuously compensated by the water contained in the reservoirs arranged in the fore compartment 30 of the gas-meter; the rising of the water-level, caused by condensation of water-vapor, is prevented by a tube that leads the superfluous water into the water-box; the height of the water-level in the gas-meter may be observed 35 at any moment, while there are no apertures through which unmeasured quantities of gas may be taken from the meter.

In order to enable my invention to be fully understood, I will proceed to describe the 40 same by reference to the accompanying drawings, in which—

Figure 1 is a front view of the gas-meter, having the front wall of the fore compartment and the water-box removed. Fig. 2 is 45 a vertical section on line A' B' of Fig. 1. Fig. 3 is a horizontal section of the fore compartment on line C' D' of Fig. 1; and Figs. 4, 5, 6, and 6^a show details of the gas-meter, partially in section.

50 The back chamber A with the drum of sheet metal B, the shaft a of the latter carrying on its part projecting into the fore com-

partment the worm b with the toothed wheel e, the spindle c in the socket d, and the counting device g with the liter-wheel f, and those 55 parts on which the above-named organs rotate, are constructed in the same manner as in the well-known wet gas-meters, while some other details are also of the same construction, but not shown in the drawings, for rendering the latter more intelligible.

Underneath the fore compartment C is, as usually, the water-chamber D, communicating directly through the bent tube E with the said compartment C. The mouth of this tube 65 is situated as close as possible to the partition-wall and very near to the lowest allowed water-level in the gas-meter, which is indicated in the drawings, Fig. 1, by line x x. The tube E, made of easily-flexible metal, is secured in the bottom of the box and suspended by means of the rod F on the cover of the compartment C. At both sides of this tube, on the cover of the fore compartment C, are arranged two water-reservoirs G and H.

70 The reservoir H, projecting deeply below the water-level, contains a float K, while the other reservoir G is above the water-level and serves for filling the gas-meter and for maintaining the water-level in the gas-meter at a 75 constant height.

In the upper part of the reservoir H is a pipe K', having a square angular section and leading from the mouth of the gas-supply pipe, which is furnished with a cock M to the 80 valve-chamber N at the right hand of the reservoir H, and projecting, like the latter, below the water-level. The valve o is supported in the valve-chamber N by a circular seat, under which is situated the mouth of 85 the siphon P. The latter extends, as in the usual known wet gas-meters, deeply into the water-chamber D, while a knee-pipe adapted to the said siphon passes through the partition-wall and projects through an aperture 90 arranged in the drum B above the water-level into the fore space of the drum. By this means a direct connection is established between the valve-chamber N and the fore space of the drum B. It is therefore impossible that 95 any quantity of gas penetrates without being measured into the fore compartment C or into the water-box D.

100 The valve o is by means of a hinge fastened

to the rod R, (see Fig. 1,) passing through an opening arranged in the bottom of the chamber N, while the other end of the rod R is secured to a beam S, not far from the fulcrum 5 of the latter. The float K is connected by the rod R' with one end of the beam. For this purpose a small opening o' is arranged in the bottom of the reservoir H, through which passes the rod R'. The other end of the 10 beam is connected with the rod R², passing through the reservoir G and projecting into an air-tight closed small box H', where, by means of a lever h, it rotates the shaft a', carrying the hand W, and moves the latter on a dial-plate arranged in front of the box H'. The socket K², made of sheet metal, surrounding the rod R², projects below the water-level x x, and is hermetically cut off from the reservoir G. The float K, of cylindrical shape, 15 has a flat or somewhat hollowed bottom. It is firmly secured to the rod R' and moves between the vertical guide-rods s s.

The reservoir G is provided with an orifice through which the gas-meter is filled. The 20 orifice is closed by a filling-screw V. To the bottom of this reservoir is fastened a short pipe d', projecting below the water-level x x. A chamber v, containing the pipe E', is arranged in the reservoir G. One end of the 25 pipe E', made of easily-flexible metal, is secured in the vertical wall v' and discharges into the reservoir, while the other end, which is bent, is connected, like the pipe E', with the rod F, and extends about 1.5 millimeters 30 above the mouth of the pipe E. The two pipes E and E' are in this way firmly connected with the rod F, and the height of the same is adjustable between certain limits. After the said pipes having been adjusted by 35 experiment; and after the nut on the upper end of the rod F and this rod itself having been soldered to the cover of the fore compartment C, as shown in Figs. 1 and 2 of the accompanying drawings, the position of the 40 pipes E and E' cannot be altered by removing the gas-meter from one place to another, or by any other cause. The pipe d', situated above the cover of the fore compartment C in the counting-box, puts the two reservoirs 45 G and H in communication with each other, so that the pressure in the reservoir G is equal to that in the reservoir H.

The connection between the fore and back compartments is established by means of a 50 small opening o², arranged in the lower part of the partition-wall. All the other openings in the latter below the water-level, as the opening through which passes the shaft a, are as small as possible. By this means I 55 attain that a difference of the water-level in one of the two compartments cannot be transmitted immediately to the other compartment.

The measured gas flows through the opening o³, Figs. 1 and 2, arranged in the upper 60 part of the partition-wall, from the back compartment A into the fore compartment C, and

thence through the pipe E into the water-chamber D. The gas-delivery pipe, provided with a cock M', is attached to the top of the 70 back compartment A.

As illustrated in Figs. 1 and 2, a rectangularly-bent tube x x' is horizontally arranged at a suitable height y y, Fig. 1, on the front wall of the water-chamber D. Fig. 4 shows 75 a top view of the tube x x', closed at x', and provided only at its lower wall with a small opening x², while at x the tube is closed by means of a screw-stopper V'.

At a short distance from the opening x² a 80 vertical partition-wall m n is arranged in the tube, extending not entirely up to the horizontal axis of the tube, and having for its purpose to prevent that the opening x² be accessible from the outside, whereby the water-level in the water-chamber D could be influenced by incompetent persons. 85

Near the mouth x a small conical backward overhanging pipe p is arranged on the tube x x', through which air is introduced into the 90 water-chamber D when water is flowing out therefrom. Should the pipe p be choked, it may easily be cleaned after the screw-stopper V' has been screwed off.

As hereinafter will more fully be described, 95 the gas-meter works in such a manner that when used by reliable persons the valve o, with the rod R, may be dispensed with; but in this case a device must be applied for sealing the filling-screw V or for rendering it in- 100 accessible. For this purpose a flange z, with holes i, is arranged above the opening, and the filling-screw is provided with threads for screwing thereon a hollow screw-head V², such as represented in vertical section in 105 Fig. 5. The screw-head is provided with a similar flange z', having also three or four holes i. For sealing the opening, a lead wire may be drawn through the holes i, being situated one over the other, and the ends of 110 the said wire may be connected with each other by means of a seal.

In the gas-meters now in use the counting 115 device is soldered to the gas-meter, so that the gager cannot examine the counting apparatus. I have made an arrangement by which the counting apparatus can readily and easily be removed and examined.

Fig. 6 is a front view, partially in section, of the counting device, and Fig. 6^a a side view 120 of the same.

The two flat bars e' e', connecting the two 125 plates g of the counting device with each other, are provided each with two conical holes r r. Upon the cover of the compartment C are arranged at a suitable distance from each other two vertical supports u u, each of which is provided with two round vertical conical points. The two holes r r receive these conical points. So a sidewise 130 movement is prevented.

In order to prevent a rising movement between the two rods of each support u, a strong spring q is arranged, provided with a

triangular cam q' , Figs. 6 and 6^a, which hold the horizontal bars down on the supports $u u$. By these means the counting device is firmly secured upon the fore compartment C, and it 5 may easily be removed in order to be revised by bending sidewise the springs $q q$.

To put this gas-meter in action and to fill the same, the cocks M and M' are closed and the screws V and V' are screwed off. The 10 water poured in at V flows then through the reservoir G into the fore compartment C, and thence through the opening o^2 into the back compartment A. As soon as the water has risen up to the line $z z$ it passes through the 15 pipe E into the water-chamber D until it flows over at z , whereupon the opening at z is closed. When still more water is now poured in, the level of the latter will rise by the height of the convex meniscus formed at 20 the mouth of the pipe E. The mouth of the pipe E', which is so much higher, is closed. The air is then compressed in the compartments, and the water will rise in the reservoirs until it flows over at V. This opening 25 is then closed, and the water which may have entered still into the water-chamber D through the pipe E is evacuated through V'. In the meanwhile the float K is raised by the water mounting in the reservoir H, and has opened 30 the valve o , so that when the cock M is opened the gas is free to enter. After having opened, then, the cock M', the gas-meter is put in action.

When by any cause—such as indicated in 35 the beginning of this specification—the water-level in the fore compartment C has fallen just below the lowest allowed level $z z$, the convex meniscus at the mouth of the pipe E' will be broken and gas will pass into the reservoirs, forcing the water out of the latter. Water will enter then from the reservoirs into this chamber until, by the rising water-level, the convex meniscus is formed again at the 40 mouth of E'. When the water-level rises 45 higher than the height of the meniscus at E, the excess of water will flow into the water-chamber D. The limits between which these two levels move are very narrow, so that the level may be considered almost as a constant 50 one. I am enabled by this means to measure the gas very exactly. The dimensions of the reservoirs are so chosen that the differences produced by evaporation can be compensated at least during six months.

55 As it is not probable that in well-constructed

gas-meters the water-level will fall below the line $z z$, and that the reservoirs G and H will become entirely empty, and as the gas-meter is to be filled only once a year, as already has been mentioned, the valve o and the rod R may 60 be dispensed with when the gas-meter is confined to the care of honest persons. The costs of manufacturing the gas-meters are considerably reduced by this; but in this case the screw V is to be covered with the above-described screw-head, (see Fig. 5,) and their flanges z and z' are to be sealed together. Should, however, within this time the water fall below the line $z z$, the hand W, connected to the beam S, will indicate this immediately, 70 and the reservoirs are then to be filled again in the above-described manner.

Unmeasured gas cannot enter the fore compartment C or the water-chamber D, or be taken out from the latter through openings arranged 75 therein. The gas-lamps are prevented, furthermore, from flickering, as the water cannot ascend up to the point where the two branches of the siphon P meet. A decrease of gas-pressure cannot take place in this gas-meter 80 more than in an ordinary one.

The way of fixing the counting apparatus enables the gager to revise and examine the apparatus very easily, whereby a security is afforded against a faulty construction of the 85 apparatus and an exact measuring attained.

Having now fully described and ascertained the nature of my said invention, I claim and desire to secure by Letters Patent—

1. In a wet gas-meter, the combination of 90 two reservoirs G and H, one of which projects below the water-level, while the other is arranged above, with pipe d^2 connecting the two reservoirs, substantially as specified.

2. The combination of reservoir H with float 95 K within the same, and with rod R', lever S, rod R, and valve o , and with rod R², lever h , and indicator W, substantially as specified.

3. The combination of reservoirs G H with 100 pipes E E', rod F, connecting said pipes, and with compartment C and water-chamber D, connected by pipe E, and with reservoir G, inclosing pipe E', substantially as specified.

In testimony whereof I have signed my name to this specification in the presence of 105 two subscribing witnesses.

BERNARDUS PETRUS MOORS.
